KNICK-KNACK SHELF

William R. Hardin, P.O. Box 198, R.D. 1,
Litchfield, Ohio 44253

Filed Oct. 21, 1965, Ser. No. 87,676

Term of patent 14 years

(Cl. D33—3)

Fig. 1

Fig. 2

Fig. 3

Fig.4

Fig. 5

FIG. 1 is a front perspective view of a knick-knack shelf showing my new design;

FIG. 2 is a top plan view;

FIG. 3 is a rear elevational view;

FIG. 4 is a side view; and

FIG. 5 is a bottom plan view.

The side opposite from that shown in FIG. 4 is a mirror image thereof.

I claim:

The ornamental design for a knick-knack shelf, as shown and described.
